DAVID WIGGER, OF NEW YORK, N. Y.

Letters Patent No. 70,930, dated November 12, 1867.

IMPROVED BELT-FASTENER.

The Schedule referred to in these Letters Patent and making part of the same.

TO ALL WHOM IT MAY CONCERN:

Be it known that I, DAVID WIGGER, of the city, county, and State of New York, have invented a new and improved Belt-Fastening; and I do hereby declare that the following is a full, clear, and exact description thereof, which will enable others skilled in the art to make and use the same, reference being had to the accompanying drawings, forming part of this specification.

Figure 1 represents a side view of my improved belt-fastener.

Figure 2 is a sectional view of the same, the plane of section being indicated by the line x , fig. 1.

Figure 3 is a plan or top view of the same when applied to broad belts.

Similar letters of reference indicate corresponding parts.

This invention relates to a new belt-fastener, which is so arranged as to be easily opened, and which when closed can be securely locked, and which is of great strength and durability.

The invention consists in the use of two metal plates, secured respectively to the ends of the belt by means of rivets or otherwise. The plates project beyond the ends of the belt, and are bent so as to form hooks, one plate being bent up, the other down. By means of these hooks the ends can be easily connected by sliding the hooks together. The latter are so bent that they can only be disengaged by moving them aside. A bolt is arranged in one of the plates, which, when the ends are to be locked, is pushed into a notch provided in the opposite plate 1.

A A' are the two ends of a belt or strap, made of leather or other suitable material. B B' are metal plates, riveted or otherwise secured to the ends A A' respectively. They are secured to the outside of the belt, (fig. 2 is reversed,) and project over the ends of the belt, as shown. The ends of the plate are bent respectively up and down, and then back, as shown in fig. 2, so as to form hooks. When locked, the back of the hook on B' will be so close to the end A of the belt, or to some projection formed on the plate B, that the hooks can only be disengaged by sliding them apart, as indicated in fig. 1.

It will be seen that the ends of the belt can thus be easily disengaged, and also firmly locked by means of a sliding bolt, a , secured to the plate B, and fitting into a notch, b , in the plate B', as shown. The under side of the belt will be perfectly plain and smooth, and will work easy. This fastening is easier applied, simpler, cheaper, and handier than the ordinary lacing or other fastenings. On broad belts two or more sets of plates, B and B', may be used, as is indicated in fig. 3.

I claim as new, and desire to secure by Letters Patent—

1. The plates B B', when firmly secured to the ends of the belt, and when shaped as described, so that they can only be disengaged by moving the ends of the belt aside, substantially as herein set forth.

2. The plates B and B', when made as set forth, in combination with the bolt a , the same being made and operating substantially as and for the purpose herein shown and described.

D. WIGGER.
